UNITED STATES PATENT OFFICE

GEORGE M. RAY, OF NEWTON CENTER, MASSACHUSETTS, ASSIGNOR TO BANCROFT-
WALKER CO., A CORPORATION OF MASSACHUSETTS

METHOD OF MAKING SHOES

Application filed January 9, 1930. Serial No. 419,594.

This invention particularly relates to certain improvements in the process of making shoes disclosed in my prior Patent No. 1,641,782, dated September 6, 1927, in which 5 a suitably curved steel shank stiffener, which is practically inflexible, is secured to a flexible inner sole, conforming the latter thereto throughout its shank portion, then securing the inner sole to the bottom of the last, after 10 which the usual operations are performed, this method having important advantages over the usual method of securing the stiffener to the inner sole after the latter has been secured to the last.

15 For the purpose of enabling workman to position the stiffener correctly on the inner sole, the inner sole die has been constructed to form notches in the edge of the sole to indicate the position of the front end of the 20 stiffener, and, while it is true that if the stiffener is first secured in the correct position on the inner sole and then the latter is secured in the correct position on the last, the stiffener will be correctly located in the finished 25 shoe, as a practical matter difficulty has been encountered in manufacturing shoes by this process due to the incorrect positioning of the stiffener in the shoe. This is likely to occur primarily by setting the stiffener too far forward, or too far back with relation to the 30 indicating notches in the inner sole and by setting the inner sole either too far forward, or too far back on the last bottom, and, while the incorrect positioning of the stiffener on 35 the inner sole may sometimes be neutralized by an incorrect positioning of the inner sole on the last, so that the stiffener will be correctly positioned in the shoe, on the other hand the inaccurate positioning of one is liable to be increased by the inaccurate positioning of the other, while an inaccurate positioning of either is likely to occur. If a shoe 40 has a high heel, there is necessarily a sharp bend in the shoe bottom at the ball line, or 45 line where the front end of the shank part meets the fore part. The metal stiffener, to be sufficiently effective, and as shown in said prior patent, extends from a point beneath the heel seat, throughout the length of the shank 50 and for a short distance beyond the vertex

line of the angle between the shank part and the forepart, or to the break-line where the shoe bends in walking, the stiffener being formed with a bend near its front end which corresponds to the angular relation between the shank and fore part above referred to. When correctly positioned, the flattened front end of the stiffener should be in position to correspond thereto, so that the flattened front end portion of the stiffener will lie flat on the forepart of the inner sole, when the shoe is finished, otherwise, if the stiffener is set back towards the heel from the correct position, the front end of the stiffener is likely to press in against the inner sole and make it uncomfortable to the wearer, or, if it is set too far forward, which, in practice, seems to occur more frequently, the front end of the stiffener will be pressed out against the outersole, so as to detract from the appearance of the shoe and cause the outer sole to be worn through at this point, after being worn for a comparatively short time.

The object of the present invention is to improve the process of my said prior patent, 75 so that inaccuracies of adjustment, either of the shank stiffener, or of the inner sole may be corrected at a subsequent time in the process.

I accomplish this object primarily by attaching the stiffener to the inner sole in a manner which permits a slight longitudinal adjustment thereof on the inner sole after the latter has been secured in position on the last, then adjusting the stiffener with relation to the last, so that its front end portion will lie flat on the sole forepart and then securely connecting the stiffener to the inner sole by means which positively prevent longitudinal movement of the stiffener on the inner sole in either direction.

For a more complete disclosure of the invention reference is now made to the following specification in connection with the accompanying drawing, in which:

Fig. 1 is a plan view of a shoe inner sole showing a preliminary step in the process.

Fig. 2 is an edge view thereof.

Fig. 3 is a longitudinal sectional view of the inner sole applied to a last.

Fig. 4 is a similar view showing a further step in the process.

Fig. 5 is a cross sectional view at line 5—5 of Fig. 2.

According to my present invention the usual form of initially flexible inner sole *a* is provided, which is died out to conform to the outline of the bottom of the last and is preferably provided with indicating notches as *b*, or some other conveniently provided mark to assist the operator in positioning the metal shank stiffener in approximately the correct position, a shank reinforce *c* being preferably secured to the sole, which may be considered as a part thereof. A metal shank stiffener *d* is provided, which is similar to that disclosed in said prior patent, being provided with flattened portions *d'* *d''* at its front and rear end respectively, the side edges of which are parallel. The intermediate portion of the stiffener is curved transversely to give it stiffness and it is curved longitudinally to correspond to the longitudinal curvature of the shank portion of the last to which it is to be applied.

In carrying out my improved process the stiffener *d* is placed in position on the inner sole, with its front end approximately in a line between the notches *b*, and in a position in which it extends along the middle portion of the shank portion of the sole. The stiffener is then secured in this position by a pair of U-form staples *e* which are arranged astride the stiffener, one adjacent each end thereof, the prongs of the staples being driven through the inner sole and clenched on the opposite side thereof, as shown in Fig. 5. The stiffener thus conforms the inner sole to its longitudinal curvature and the latter is then secured to the last by tacks which are driven therein at each end of the stiffener, as shown in Fig. 3.

The staples *e*, by which the stiffener is secured to the inner sole, positively hold the stiffener against transverse movement on inner sole and also by a strong frictional engagement, to hold it against longitudinal movement thereon, so that it can only be moved in this manner when a substantial force is applied thereto. While the stiffener may be located in the correct position longitudinally with relation to the last bottom, when the inner sole has been secured to the last, as previously explained, it is liable to be located too far forwardly, for example, in which case its front end portion *d* will be held out of engagement with the inner sole portion directly beneath it, and is also likely to extend away therefrom at a slight angle, as indicated in Fig. 3, so that if the outer sole were attached, the front end portion of the stiffener would press outward against the inner sole and force it outward at a portion thereof which receives the greatest wear, with the result that when the shoe was worn the

front end of the stiffener would cause excessive wear of the outer sole at its point of engagement, and soon cause a hole to be worn therethru. Also the protruding end of the stiffener would be likely to prevent satisfactorily leveling of the shoe bottom.

To obviate the above difficulty, after the inner sole has been secured to the last bottom, if it is found that the stiffener is incorrectly positioned, as shown for example in Fig. 3, the stiffener is forced beneath the staples *e* until its front end portion rests firmly against the inner sole surface, as shown in Fig. 4, and then the stiffener is firmly secured against further longitudinal movement by driving a tack, as *f*, thru a hole, as *g*, which is provided, at some point in the stiffener, preferably in its rear portion *d''*, as shown in Fig. 4, the tack being clenched against the usual metal plate on the last bottom as shown.

The subsequent operations of lasting applying the cuttersole etc. are then performed in the usual manner, with the result that the stiffener will be correctly located in the finished shoe and all the desired and expected advantages of the process disclosed in my said prior patent will be secured.

I claim:

The method of making shoes which consists in providing a flexible inner sole and a substantially inflexible metal shank stiffener which is curved longitudinally to conform to the longitudinal curvature of the last bottom and is adapted to extend from a point over the heel to points adjacent the transverse line of flexure at the ball, initially positioning the stiffener on the inner sole and securing it thereto in a manner to prevent transverse movement and frictionally hold it thereon against longitudinal movement, securing the inner sole on the last bottom, then repositioning the stiffener with relation to the last by adjusting it longitudinally against the frictional engagement of its securing means, then positively securing it against longitudinal movement from its adjusted position, and then completing the shoe.

In testimony whereof, I have signed my name to this specification.

GEORGE M. RAY.
